THREAD CONTROLLER FOR SHUTTLE
CHANGING LOOMS

Lewis S. Vose, Worcester, Mass., assignor to
Crompton & Knowles Loom Works, Worcester,
Mass., a corporation of Massachusetts

Application January 8, 1935, Serial No. 873

16 Claims. (Cl. 139—227)

This is a continuation in part of my copending application Serial No. 610,409. This invention relates to improvements in shuttle changing looms and it is the general object of the invention to improve the operation of such looms with respect to the weft of the outgoing empty shuttle.

In a certain well-known form of shuttle changing loom the lay remains at rest in rearward position during the replenishing period with the warp shed open. Under these conditions if the yarn extending from the outgoing shuttle is tightened or slackened because of irregular movements of the ejected shuttle there results a defective pick in the cloth. It is an important object of my present invention to provide a thread cutter and clamp effective to grasp and hold the thread of the outgoing shuttle before the tension in the weft can be changed substantially by shuttle movement, and then cut the thread to prevent movement of the shuttle from tightening it.

It is a further object of my invention to provide a thread controlling device, which may be either a clamp or a cutter or both combined, which shall be actuated by being projected against the lay when the latter is stationary and in back position. With the lay at rest the weft which extends along the race is stationary and it is more likely to lie in a given position on the lay, thereby rendering more certain the operation of the cutter and clamp.

It is a further object of my invention to provide a thread controller which can be actuated by the shuttle carrier of a multicolor weft replenishing loom, the carrier starting its motion at a point in the cycle of the replenishing operations early enough to project the cutter or clamp to operative position with respect to the thread of the outgoing shuttle before the latter has been moved appreciably on the lay. In this way the thread is maintained in position where it can be engaged by the clamp or cutter and also the tension previously mentioned remains substantially unchanged.

It is a further object of my invention to provide the cutter or clamp with a stationary mounting so that at the time of operating on the weft the support as well as the lay will be stationary and a rate of motion for the thread engaging elements most favorable can be attained with assurance that this rate will not be disturbed due to lay motion.

In the particular loom shown herein the replenishing operation is accomplished by two shuttle advancers the first of which is a carrier movable under a plurality of reserve shuttle stacks,

while the second is a conveyor which takes the shuttle from the carrier and moves toward the lay. If the depleted shuttle fails to reach a given point along its normal path of discharge the conveyor will be locked in forward position and prevented from having a normal replenishing stroke. Under these conditions looms of the type mentioned would ordinarily continue to operate despite the fact that the shuttle ejecting mechanism might be deranged or otherwise unable to eject the shuttle. It is a further object of my present invention to operate the thread cutting mechanism independently of the conveyor whenever a replenishment is called, so that even though the shuttle is not ejected through defective mechanism, the thread will be cut and the filling stop motion, either of the side or center type, will stop the loom. The weaver can then correct the fault. This result I achieve by requiring the cutter to operate in conjunction with the carrier, which is that part of the replenishing mechanism operating independently of shuttle ejection.

If the outgoing shuttle should leave an incomplete pick of filling in the shed it is desirable to prevent resumption of weaving so that the weaver can remove the faulty thread before it is beaten into the cloth. Under these conditions there will be no thread for the thread clamp to catch and there is an opportunity to utilize this condition in connection with a side filling fork to prevent restarting of the loom. The usual side weft fork is operated regularly from the bottom shaft of the loom and would be superfluous in the better class of looms which have center stop motions. I prefer to keep my side fork normally idle and preferably in a forward position where it will not engage the weft in normal loom operation. During a shuttle changing operation the fork becomes operative and the thread clamp moves the thread of the old shuttle forwardly to a position where it can coact with the fork. If no weft is present the stop motion acts through appropriate mechanism to prevent restarting of the loom.

It is a further object of the invention to operate the thread clamp so that it will open in forward position while the lay is in rear position, thereby releasing the weft end of a previous shuttle changing operation from a position where it cannot later be dragged into the shed.

Shuttle changing looms such as shown herein have a brake mechanism to stop the loom with the lay in rear position. Due to wearing of the brake or inaccurate setting the loom may come to rest with the lay somewhat in front of back center. The thread cutter and clamp are pro-

jected toward the lay and depend for their operation upon engagement with the lay. It is a further object of my invention to provide a yielding support for the cutter and clamp which will permit correct operation of these parts regardless of the position of the lay.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a portion of a multi-color shuttle changing loom having my invention applied thereto,

Fig. 2 is a view similar to a portion of Fig. 1, illustrating the manner of operating the thread cutter and clamp,

Fig. 3 is a top plan view of a magazine and parts of the lay and breast beam, showing the relation of my cutter and clamp to the magazine, lay and selvage trimmer,

Fig. 4 is an enlarged horizontal section on line 4—4 of Fig. 2,

Fig. 5 is a detail of the jointed parts of the lever looking in the direction of arrow 5, Fig. 2,

Fig. 6 is a vertical detail section on line 6—6 of Fig. 4, and

Fig. 7 is a view similar to a portion of Fig. 1 with the magazine and cutter clamp omitted, showing the side filling motion and its relation to the loom starting mechanism.

Referring to the drawings, I have shown a loom frame 10, lay 11, change shaft 12, and a multi-color magazine 13 mounted on the loom frame. By means of mechanism not shown herein but well understood and set forth in my co-pending application Serial No. 593,814, the lay is at rest during the replenishing period.

The magazine has reserve shuttle stacks 14, and mechanism set forth in my co-pending United States application Serial No. 603,051 releases a selected shuttle so that the same falls on a carrier 15. Levers 16 pivoted one at each side of the magazine as at 17 and actuated by a vertical rod 18 move the carrier first in a forward direction to the left as viewed in Fig. 1, and then back to the normal rear position whenever a change of shuttles is called. A lever 19 controlled by a cam 20 on the change shaft may effect this result.

A conveyor lever 21 pivoted at 22 on the frame is actuated by a cam 23, and is effective to take a shuttle from the carrier and advance it toward the lay by means of a conveyor 27 on lever 21. A lock notch 24 in the conveyor lever is positioned to receive a hook 25 pivoted to a receiver box 26 at 27. A plate or vane 28 positioned in the path of the ejected shuttle moves with the hook and the latter is counter-weighted so that it tends normally to enter the notch. The conveyor lever and counterweight 29 co-act to prevent the shuttle from dropping into the box until after the conveyor lever has moved rearwardly out of restraining position with respect to the counter-weight.

A shuttle guiding apron 30 is secured to the under side of the lay and extends to the back part of the receiver box in such a position as to direct the ejected shuttle toward the plate 28. The conveyor lever may be normally in the position shown in Fig. 1 and during the first part of the replenishing operation the notch 24 will be moved to the left so that the counter-weight can

move the hook into the notch if no shuttle is resting on the plate 28. The cam 23 is timed to start the rear or right hand movement of the conveyor lever as viewed in Fig. 1 after the shuttle has had time to reach the plate 28, and failure of the shuttle to be properly ejected will permit the counter-weight to move the hook into the notch and the conveyor lever will therefore be locked against rearward movement, thus preventing transfer.

The shuttle ejector mechanism is mounted on the lay and comprises a box front 35 carried by a lifter lever 36 pivoted at 37 to the lay. A rod 38 connected to lever 39 is depressed by cam 40 on shaft 12 to raise the box plate 35. The latter moves to a position above the shuttle before engaging a screw 41 on ejector lever 42 pivoted at 43 to the lay. Further upward movement of the lever 36 therefore rocks the ejector in a clock-wise direction as viewed in Fig. 1 to force the ejector finger 44 against the shuttle S, thereby moving the latter under the plate 35 and forwardly of the lay, causing the shuttle to descend along the apron toward the plate 28.

A lever 45 may operate upon starting rod 46 when moved by cam 47 on shaft 12 to effect resumption of loom operation after the change shaft has completed one revolution. The shaft may require a half a dozen picks or more for its rotation, depending upon the time allotted for replenishment. The matter thus far described may be as set forth in my last named co-pending application.

In carrying my present invention into effect I provide means for controlling the weft of the ejected shuttle so that the same may be clamped and cut and for controlling the loom through the weft. Accordingly, I form the magazine with a rearwardly extending horn 50 to which is pivoted at 51 a bell crank lever 52 having an upper forward arm 53. This arm has an adjustable sliding driving connection with a corresponding arm 54 on one of the levers 16, namely, the inner lever. A cutting and clamping arm 55 pivoted as at 56 to the arm 52 is shown in detail in Fig. 5. A tension spring 57 holds the arms 52 and 55 yieldingly in the position shown in Fig. 1, and a stop finger 58 on arm 55 bears against a part 59 of arm 52 to limit action of the spring.

The lower end of arm 55 is formed with a cutting edge 60 and has pivoted thereto as at 61 a movable cutting and clamping jaw 62, having a cutting edge 63, see Fig. 6. A thread clamp 64 is movably mounted on the arm 55 and is held yieldingly in position by a spring 65. The clamp 64 is positioned by the pivot 61 and a guide pin 66 carried by the arm 55.

An operating finger 67 extends downwardly and forwardly from the cutter jaw 62 and is positioned for engagement with a surface carried by the lay. A trip finger 68 also moving with the jaw is positioned to engage a releasing hook 69 pivoted as at 70 to the magazine and has a stop finger 71 to engage a stop pin 72 on the magazine to limit downward movement of the hook. The lay may be provided with a notch 73 appropriately formed to receive the cutting and clamping unit.

In Fig. 3 I show a conventional form of selvage trimmer mounted on a temple 75 and having a blade 76 which operates in the usual manner to cut the weft ends extending from the selvage toward the magazine several picks after replenishment. The selvage trimmer can be of any approved form and operates subsequent to the operation of my present cutter and clamp.

In operation, the loom will be brought to rest by the weft detector, not shown, with the lay in rear position, not necessarily in full back center position. Mechanism not shown herein but similar to that shown in my aforesaid applications will start shaft 12 rotating and cause forward motion of carrier 15 with attendant down motion of arm 54 to project the cutting and clamping unit rearwardly. As the unit moves rearwardly the hook 69 will engage the releasing finger 68 and open the clamp and cutter, as shown in Fig. 2, to define notch 80 for the weft W. As the unit continues to move toward the lay, finger 67 will strike the lay and close the cutter and clamp, severing the weft and clamping that part of it which extends toward the cloth.

The setting of the parts is such that when the lay is in rearmost position the spring 57 will yield somewhat when the cutter closes. This insures 20 complete closure for all reasonable positions of the lay.

It is to be understood that this operation of the cutter and clamp occurs during the first part of the replenishing period before the ejected shuttle leaves the lay, or has had substantial movement 25 relatively to the lay. I prefer to time the operations so that the notch 80 will reach rear position and close on the thread before the shuttle has entirely left the lay, this arrangement insuring entry of the weft of the outgoing or ejected shuttle in the notch and also before the tension of the weft can be changed materially. At each cutting operation the lay is at rest with the weft undisturbed by lay motion and therefore in practically 30 the same position for each shuttle changing operation. Since the lay is at rest the rate of cutting is the same for all shuttle changes.

Continued operation will move the carrier 15 rearwardly with simultaneous forward motion 40 of the cutter unit until the latter reaches normal position as shown in Fig. 1. The rear face of hook 69 is cam shaped to ride up and over the opening finger 68. The clamp now holds the weft end diagonally as shown in Fig. 3 and in this 45 position the selvage trimmer will cut the thread within a pick or two after the loom restarts. The clamp holds the thread 81 until the next shuttle change, whereupon it releases the weft end at the beginning of the backward motion while the 50 lay is back. The falling thread therefore does not fall on the lay.

A center filling stop motion 110 is shown in Fig. 2 and performs the usual function of stopping the loom if weft is not present in the shed. Such 55 a condition will exist if the unit cuts the thread but the shuttle fails to be ejected due to defective mechanism, and the weaver can then determine the cause of loom stoppage.

Another feature of my invention which depends 60 upon the cutter unit is that which relates to the side stop motion control which prevents restarting. As shown more particularly in Fig. 7 a filling stop motion T has a slide 83 to which is pivoted a usual fork 84. A lever 85 pivoted at 86 is rocked by forward motion of the slide to the left in Fig. 7 to raise a link 87 connected to a rock arm 88. The latter is normally down to allow a pin 89 in a lever 90 to occupy a notch 91 which extends up from a slot 92 in a rod head 93. Lever 70 90 is secured to the shipper shaft 94, while rod head 93 is on a rod 46 which extends back to an arm 96 of a restarting lever 45. A collar 98 on the rod is positioned to be pushed rearwardly by arm 96. A stop motion lever 99 carries a notched head 100 to coat with the loop 101 of the fork

and is rocked by a cam 102 on shaft 12. When the shaft is at rest the head 100 is in rear position, and the fork is normally far enough forward not to coat with the weft at beat-up, although this is not a necessary relation.

When the loom has stopped for a shuttle change arm 98 will rock to the left, as in Fig. 7, and draw collar 98 toward arm 96. Near the conclusion of the shuttle changing operation lever 45 will rock to move arm 96 to the right, Fig. 7, and if 10 pin 89 is in notch 91, arm 90 and shipper shaft 94 will be moved to running position. If the rod head 93 should be raised, the loom will not be restarted, since rod 46 will have an idle motion and slot 92 will move along pin 89. Such an operation 15 is desirable if the last pick of weft to be laid by the outgoing shuttle should be defective.

The filling fork 84 determines whether the loom shall be restarted. If weft extends from the selvage to the thread clamp it will tilt the fork 20 and lift loop 101 above the head 100. Cam 102 will rock lever 99 to advance the head, moving it to the left in Fig. 7, and slide 83 will remain at rest, permitting pin 89 to remain in notch 91. Should weft be absent on the shuttle changing 25 pick, however, the fork will not be tilted and loop 101, connected as usual to the slide 83, will advance the latter and cause lifting of arm 88 when cam 102 rocks lever 99. This is the condition as already described, which prevents restarting of 30 the loom.

It should be noticed, by reference to Fig. 3, that the fork 84 is far enough in front of the lay to avoid contact with the weft during normal weaving and that reliance is had on the thread 35 clamp to move the thread of the outgoing shuttle against the fork. This latter feature is so even should the fork be in the usual position, because the lay stops in back position away from the stop motion and the clamp operates to move 40 the thread against the fork without requiring forward motion of the lay.

From the foregoing it will be seen that I have provided a simple form of cutter and clamp which is projected against a stationary lay when the 45 latter is in rear position to sever the weft of the outgoing shuttle and to clamp the same, thereby maintaining the tension of the weft in the shed which is open at the time, while permitting the ejected shuttle to carry the weft end connected 50 thereto into the receiver box without tending to pull the weft end through the clamp to tighten the pick in the shed. It will also be seen that at the next replenishment the weft end is released when the cutting and clamping unit is near its 55 foremost position and while the lay is at rest in rear position. Also, it will be seen that the cutter and clamping units perform their operations whenever replenishment is called for regardless of the operation of the conveyor lever, so that 60 even though an exchange of shuttles is prevented from some improper operation of the loom, the cutter will nevertheless sever the weft of the shuttle. When the shuttle is picked to the opposite side of the loom upon resumption of 65 weaving the center filling fork will stop the loom and the weaver can detect the cause for the defective replenishing operation. The cutter and clamping parts are made yieldable on the arm 52 so that engagement with an 70 ejected shuttle will not result in breakage, spring 57 being provided for this purpose. The clamp is set to yield even with the lay in rearmost position in order to insure correct operation for any 75 probable position of the lay. It will further be

- seen that the invention is particularly adaptable to a multicolor shuttle changing loom which employs the carrier 15. Furthermore, a side filling fork is provided which operates in conjunction with the thread clamp to prevent restarting of the loom should the last pick laid by the outgoing shuttle be incomplete. While I have shown a specific form of cutter and clamp yet I do not wish to be limited to the same.
- 10 Having thus described my invention it will be seen that changes and modifications may be made therein by those skilled in the art without departing from the spirit and scope of the invention and I do not wish to be limited to the details here-
15 in disclosed, but what I claim is:
1. In a shuttle changing loom which stops to effect shuttle change and then resumes weaving, a reserve shuttle magazine, a lay which is at rest during the time that the depleted shuttle is 20 expelled from the loom, means to move a fresh shuttle toward the lay while the loom is stopped, and a thread cutter and clamp movable by the means into engagement with the stationary lay, said engagement causing the clamp to catch and 25 hold the weft of the outgoing shuttle and preserve the tension of the weft in the shed, and sever the weft of the expelled shuttle from the weft in the shed.
  2. In a shuttle changing loom which stops with the lay in rear position during the shuttle changing period, a combined thread cutter and clamp mounted independently of the lay, and means to project the cutter and clamp when open toward and against the stationary lay to cause 30 the latter to close the clamp and sever the weft of the depleted shuttle.
  3. In a shuttle changing loom which stops with the lay in rear position during the shuttle changing period, a shuttle changing mechanism including a part actuated during the replenishing period, a thread cutter and clamp normally independent of the lay, and operative connections between the part and cutter and clamp to move the latter while open against the stationary lay to cause the latter to close the cutter and clamp.
  4. In a shuttle changing loom which stops with the lay in rear position during the shuttle changing period, a reserve shuttle magazine, a carrier therefor to advance a shuttle from the magazine toward the lay, a combined thread cutter and clamp, and connections between the carrier and combined cutter and clamp to move the latter against the stationary lay and cause the latter to close the clamp.
  5. In a shuttle changing loom which stops with the lay in rear position, a conveyor lever to move a shuttle to the lay during the replenishing period, a weft parter to sever the weft of the depleted shuttle during said period, means to deliver a reserve shuttle to the conveyor, connections between the parter and means rendering the latter effective to operate the parter to sever the weft independently of the conveyor, and a filling stop motion to stop the loom if the depleted shuttle is rendered active upon resumption of loom operation due to failure of the ejector.
  6. In a shuttle changing loom which stops with the lay in rear position, a depleted shuttle ejector operable during the replenishing period, a thread parter to cut the weft of the depleted shuttle during said period, a replenishing element performing its function of advancing a reserve shuttle toward the lay independently of the ejector, connections between the element and

5 part to operate the latter to cut the weft of the depleted shuttle independently of the ejector, and a filling stop motion to stop the loom if the depleted shuttle is rendered active upon resumption of loom operation due to failure of the ejector.

7. In a shuttle changing loom having a lay which remains at rest in rear position during the shuttle changing operation, a thread cutter and clamp normally closed, means to project the cutter and clamp rearwardly toward the lay when the latter is at rest, a cutter and clamp opening element effective to open the cutter and clamp during the first part of the rearward movement thereof, and a member carried by the cutter and clamp to engage the lay to close the cutter and clamp and cause the same to seize and cut the thread extending from the depleted shuttle to the cloth.

8. In a shuttle changing loom having a lay and a depleted shuttle with the weft end extending from the shuttle to the cloth, the lay, shuttle and weft end being substantially at rest with the lay in rear position during the beginning of the replenishing period, a thread cutter and clamp, 25 and means to move the cutter and clamp rearwardly during the beginning of the replenishing period to cut and clamp the substantially stationary weft at a point between the depleted shuttle and the cloth, whereby movement of the shuttle at a later time in the replenishing period is rendered ineffective to vary the tension of the weft extending from the clamp to the cloth.

30 9. In a shuttle changing loom having a lay and a depleted shuttle with the weft end extending from the shuttle to the cloth, the lay, shuttle and weft end being substantially at rest with the lay in rear position during the beginning of the replenishing period, a combined thread cutter and clamp, and means to project the cutter and clamp toward the lay to engage the latter and be operated thereby to sever the weft extending from the clamp to the depleted shuttle and to clamp the weft extending toward the cloth, whereby 35 movement of the shuttle subsequent to the cutting operation is ineffective to alter the tension of the weft extending from the clamp to the cloth.

45 10. In a shuttle changing loom having a lay which comes to rest in rear position during the shuttle changing period, the lay capable of assuming any one of a plurality of positions of rest adjacent the rearmost position, a thread cutter and clamp, means to project the cutter and clamp toward the lay to cause operation of said cutter and clamp by the lay, and a yielding connection between the means and the cutter and clamp to yield when the cutter and clamp are operatively related to the lay when the latter is in 50 any of the aforesaid plurality of positions adjacent the rearmost position.

55 11. In a shuttle changing loom having a lay movable backwardly and forwardly between front and back positions and coming to rest at or adjacent to the back position during the shuttle changing period, a thread cutter and clamp normally in forward position, means to project the cutter and clamp rearwardly while open into engagement with the lay, the cutter and clamp to be operated by engagement with the lay, and a yielding connection between the means and the cutter and clamp constructed and proportioned to yield upon engagement of the cutter and clamp 60

- with the lay when the latter is in any of its rear positions during the shuttle changing period.
12. In a shuttle changing loom which comes to rest to effect shuttle change, restarting mechanism, a filling fork, means to establish operative connections between the filling fork and the restarting mechanism, and a thread clamp to hold the thread extending from the shuttle to be ejected and effect operative relation between the 10 weft and the filling fork, the fork when weft is absent being effective through the said means to prevent the restarting mechanism from starting the loom.
13. In a shuttle changing loom which comes to rest with the lay in back position during the 15 shuttle changing period, loom restarting mechanism, a filling fork, means to establish operative connections between the restarting mechanism and the fork to prevent operation of the 20 restarting mechanism when the connections are established, a thread clamp to clamp the weft extending from the shuttle to be ejected and move said weft thread against the fork and thereby prevent the fork from establishing connections with 25 the restarting mechanism, and the means operative upon failure of the clamp to present a weft thread to the fork to establish said connections and thereby prevent the loom from resuming running after the shuttle changing period.

14. In a shuttle changing loom which comes to rest to effect shuttle change, restarting mechanism operative after a shuttle change to cause the loom to resume weaving operations, a thread clamp to give a motion to the thread extending from the cloth to the shuttle to be ejected, and means effective upon failure of the clamp to move said thread to prevent the restarting mechanism from causing the loom to resume operations.

15. In a shuttle changing loom which comes to rest to effect shuttle changing, restarting mechanism to cause the loom to resume weaving operations at the conclusion of the shuttle change, a member to be engaged by weft extending from the cloth toward the shuttle to be ejected and a 15 controller for the restarting mechanism depending upon engagement of the member by said weft to effect operation of the restarting mechanism.

16. In a shuttle changing loom which comes to rest to effect shuttle change, restarting mechanism for the loom, a member to be engaged by weft extending from the cloth toward the shuttle to be ejected and means operative upon failure of said member to be engaged by the weft to 25 prevent the restarting mechanism from restarting the loom.

LEWIS S. VOSE.
